Application filed December 9, 1892. Serial No. 454,667. Term of patent 3½ years.

To all whom it may concern.

Be it known that I, WILLIAM M. DAINTREY, a citizen of the United States, residing at New York, in the county and State of New York, have invented and produced a new and original Design for a Carpet, of which the following is a specification, reference being had to the accompanying photograph, forming a part thereof, which is a face view of a carpet showing my new design.

The design consists of a body A and a border B. The body A consists of scroll-shaped stems, ornamented with leaf forms on a ground containing fragmentary sprays of leaf and stem forms. The border B, has an inner or-

namental margin composed of a series of figures arranged in connected series and approximating a circular shape, a main portion composed of scroll-shaped stems ornamented with leaf and branch forms, and festoon figures simulating flowers of the rose type; and the border is further provided with an outer heavy margin composed of a bar figure and groupings of dot-figures, the rose figures intervening the dot and bar figures. 25 30
